E. M. HENDRICKS

COMBINED X-RAY PROTECTIVE CANOPY AND TABLE

Filed Oct. 24, 1923

Inventor
ELLIOT M. HENDRICKS.

By *Wallace F. Murray*
Attorney

UNITED STATES PATENT OFFICE.

ELLIOTT M. HENDRICKS, OF COLUMBUS, OHIO.

COMBINED X-RAY PROTECTIVE CANOPY AND TABLE.

Application filed October 24, 1923. Serial No. 670,405.

To all whom it may concern:

Be it known that I, ELLIOTT M. HENDRICKS, a citizen of the United States of America, and a resident of Columbus, in the 5 county of Franklin and State of Ohio, have invented a new and useful Improvement in a Combined X-Ray Protective Canopy and Table, of which the following is a specification.

10 This invention relates to protective devices for use in X-ray therapy.

It is generally known by those versed in X-ray therapy that the rays used must be of sufficient intensity and duration to kill 15 the disease treated, and that rays which will kill diseases will also destroy normal tissue and blood cells wherefore it is necessary to confine the rays closely to the diseased portion of the body to be treated.

20 Various means have been used to localize the exposure of the X-rays, but the devices employed have been found cumbersome, difficult of adjustment and a few have been found dangerous to the patient.

25 An object of my invention is to provide a combined protective canopy and treatment table wherein X-rays may be confined to a limited portion of the body.

Another object is to provide a device of 30 this character wherein a patient undergoing treatment is precluded from inadvertent contact with the high tension terminals of the X-ray tube.

Another object is to provide a device of 35 this character which is simple in construction and which is operated without difficulty.

These and other objects are attained by the means described herein and disclosed in the accompanying drawings, in which:

40 Fig. 1 is a side elevation of a device of my invention.

Fig. 2 is a plan view of the device.

Fig. 3 is an end elevation of Fig. 1.

45 Fig. 4 is a fragmental cross section of a modified form of my device.

The device comprises a treatment table 5 having suitable legs 6 and carrying on the upper face of the top 7 a plurality of guides 8 adjacent the longitudinal edges thereof.

50 The guides 8 are arranged in pairs and may be formed of T-irons as shown or in any suitable shape. The canopies 9 are in the preferred form made semi-cylindrical in shape and are constructed of sheet iron or sheet 55 steel with a sheet lead covering 10 mounted thereon.

The edges 11 of the canopies 9 carry short axles 12 upon which are revolvably mounted rollers 13 which in this case are shown having grooves 14 for receiving the guides 8. 60 For securing compactness I prefer to mount the axles 12 on the inner side of the smallest canopy and on the outer side of the largest canopy, the intermediate canopies carrying pairs of brackets 15 on which axles 12 are 65 mounted. It is not desired to limit the invention to the specific manner of mounting the canopies as it is within the scope of this invention to provide sharp edged rollers engaging in V-shaped guides or various other 70 mechanical equivalents thereof. The modified form suggested in Fig. 4 consists of securing the guide members 8 upon a suitable open frame comprising sides 16 and end pieces 17 the unit thus formed being adapted 75 for use upon an ordinary table 18 or it may be mounted upon suitable standards for holding this unit over an adjustable treatment table.

In operation all of the canopies 9 may be 80 telescoped at one end of the table whereupon the patient may be placed upon the table without difficulty. The sections are then rolled to cover the entire body except a narrow section containing the part to be treated. 85 If a very small location is to be treated, a strip of lead-rubber may be laid across the patient's body over the exposed portion thereof and a hole of suitable size cut in the lead rubber. 90

From the foregoing it will be noted that I have provided means to limit the X-ray exposure to the desired area and location by a unitary device which is handled with great facility. The canopies when positioned over 95 the patient, prevent him from accidentally bringing his limbs in contact with the X-ray tube and also afford protection in case of breakage of the tube. The sections of the canopy may be removed due to the comparative small size and correspondingly light weight thereof.

What I claim is:

1. In an X-ray treatment table and protective device, the combination of a table and 100 a plurality of canopies impervious to Röntgen rays adjustably mounted above the table.

2. As a new article of manufacture an X-ray protective device comprising a telescoping canopy mounted for selective adjustment above a table. 110

3. As a new article of manufacture an X-ray protective apparatus comprising an adjustable canopy impervious to Röntgen-rays for mounting above a table and positionable for selectively covering and exposing the top of said table. 25
4. An X-ray treatment table and protective apparatus comprising the combination with a table, of a plurality of telescoping 10 canopies and co-operating means carried by the canopies and the table for slidably adjusting the canopies over the table.
5. An X-ray treatment table and protective apparatus comprising the combination 15 with a table, a plurality of telescoping canopies, rollers mounted on the canopies, and guides on the table for receiving the canopy rollers for selectively positioning the canopies above the table.
- 20 6. An X-ray treatment table and protective apparatus comprising the combination of a table, longitudinally extending guides adjacent the sides of the table, canopies, and
- rollers carried by the canopies and engaging the guides for providing longitudinal adjustment of the canopies above the table. 25
7. As a new article of manufacture an X-ray protective apparatus comprising a series of semi-cylindrical canopies impervious to Röntgen-rays telescopically mounted 30 on longitudinal guides.
8. As a new article of manufacture a telescopically adjustable X-ray protective canopy for mounting over a table.
9. In a device of the class described the 35 combination with a plurality of semi-cylindrical telescoping canopies, a sheet-lead covering on each of said canopies, rollers mounted on the canopies, and spaced guides 40 for receiving the rollers for providing independent adjustment of the several canopies longitudinally above a table.

In testimony whereof, I have hereunto subscribed my name this 13th day of October, 1923.

ELLIOTT M. HENDRICKS.
